CLAIM

The ornamental design for an aquatic toy, as shown and described.

DESCRIPTION

FIG. 1 is a perspective view of the aquatic toy according to my new design.

FIG. 2 is a bottom plan view.

FIG. 3 is a left side elevational view of the aquatic toy of FIG. 1.

FIG. 4 is a bottom plan view.

FIG. 5 is a right side elevational view.

FIG. 6 is a front elevational view, the rear elevational view being a mirror image thereof; and,

FIG. 7 is another perspective view of the aquatic toy, but with the rope portions shown in limp or unextended position.

The broken lines in the drawing are for illustrative purposes only and form no part of the claimed design.
